TELEPHONE SYSTEM

Benjamin F. Lewis, Bayside, N. Y., and Alexis A. Lundstrom, East Orange, N. J., assignors to Bell Telephone Laboratories, Incorporated, New York, N. Y., a corporation of New York

Application March 22, 1940, Serial No. 325,344

14 Claims. (Cl. 179—18)

This invention relates to telephone systems and particularly to those in which automatic switching devices are used to establish conversational connections.

The objects or the invention are to facilitate the transmission of designations over telephone lines and particularly from subscribers' stations to the central office; to safeguard against false operations with respect to the designation transmission; to insure adequate control over all functions of the equipment in the central office, including the control of release of the common equipment; to maintain good transmission conditions during the sending of designations; and otherwise to obtain improvements in systems of this character.

Systems have been proposed heretofore in which codes of alternating currents of different frequencies, instead of the more usual direct current impulses, are transmitted over the line from the subscriber's station to set up the desired designations in common central office register senders. It has also been the common practice in systems using the direct-current-impulse method of sending designations to rely on the presence of the direct current flowing from the central office sender over the subscriber's line loop to hold the sender, thereby permitting the immediate release of the sender at any moment the subscriber replaces his receiver. If, however, this method of supplying direct current to the subscriber's line to hold the sender is used in a system designed to transmit the designations by frequency codes, as above noted, there is the possibility that sounds entering the microphone may modulate the direct current and produce frequencies that cause false registrations in the central office sender.

According to a feature of the present invention these difficulties are obviated by means of a system in which the direct current is removed from the subscriber's line following the seizure of the sender in the central office, and in which the sender is held independently of the line during the period of transmitting the designation currents to the sender. If the call proceeds normally, the sender receives and registers the full designation, controls the selector switches accordingly, and releases itself. However, if the calling party abandons the call before the sender has progressed to the stage where it is capable of releasing itself in the normal manner, a special frequency code is transmitted from the substation to the central office. The sender receives this special code, recognizes it as a signal that the

5 subscriber has replaced his receiver, and proceeds to release at once. This special frequency code is produced automatically by the substation transmitter as a result of replacing the telephone on its stand. The frequency transmitter may comprise a plurality of vibratory reeds for generating currents of corresponding frequencies, and the act of replacing the telephone causes the plucking of one or more of these reeds.

10 Another feature of the invention is a system of the character above described in which the replacement of the telephone plucks one or more reeds to send the special release code and also initiates the operation of a time delay mechanism. At the end of a predetermined interval, during which the special signal is being sent from the reed generator over the line, the delay mechanism opens the line, thereby disconnecting the generator and restoring the substation to its normal open-circuit condition.

15 A further feature is a system of the character described in which the resistance of the transmission circuit is held within desired limits while the designation is being sent. As above noted, the transmission circuit is "dry" during the sending period; that is to say no current flows in the circuit other than the alternating currents generated by the subscriber's transmitter. But it has been found that the numerous relay and 20 switch contacts in the transmission circuit present a much greater resistance to the alternating current signals when the circuit is "dry" than they do if the circuit is energized by the flow of direct current therein during the signal transmission. Not only is the resistance higher, but 25 it is subject to wide variations, which result in objectionable distortion of the signals. To overcome this objection, a source of alternating current of a relatively high frequency, above the 30 audible range, is superimposed upon the circuit while the designation signal currents are being sent. This superimposed current does not interfere with the signal currents since its frequency may be chosen at a value, say 30 kilocycles, which lies far beyond the range of signal frequencies. And, although relatively low in intensity, this auxiliary current flowing in the 35 transmission circuit has the remarkable effect of maintaining the resistance of the circuit at a value comparable with that obtained when direct current is flowing and also the effect of preventing resistance variations. The intensity of the auxiliary current that is necessary to accomplish these results is low enough so that no in-

terference is caused in the operation of other message or signaling channels.

These and other features of the invention will be described more fully in the detailed specification and will also be set forth in the appended claims.

In the drawing accompanying the specification, Figs. 1 to 5, when arranged in the order illustrated in Fig. 6, disclose, partly in diagrammatic form and partly in detail, an automatic telephone exchange system embodying the features of the present invention.

Fig. 1 illustrates the details of a subscriber's line equipped with a transmitter for sending telephone designations over the line in the form of alternating currents of different frequencies. This figure also illustrates diagrammatically the automatic switches in the central office which serve to establish telephone connections between subscribers' lines, together with certain relays and control equipment associated with these switches. Furthermore, this figure illustrates the link switches which serve to extend a calling subscriber's line to one of the common central office register senders; and

Figs. 2, 3, 4 and 5 disclose one of the register senders. Fig. 2 shows the controlling relays of the sender; Fig. 3 shows means for controlling the application of dial tone current to the calling line together with equipment for receiving the alternating current signals transmitted from the subscriber's station; Fig. 4 discloses the transfer relays for transferring the designation signals to the register relays; and Fig. 5 discloses the register relays on which the designations are registered.

Substation equipment

The subscriber's designation transmitter used in this system consists essentially of a plurality of reeds 100 which vibrate, when plucked, in a magnetic field to set up in a generating coil 101 currents of corresponding frequencies. These currents are sent over the subscriber's line in frequency codes to the central office sender where they are received, identified and registered. Any suitable mechanism may be provided for plucking the reeds. The mechanism illustrated in the drawings comprises a plurality of code bars 102, one for each reed, and a group of designation keys 103. If, for example, the designation characters are represented by codes of two frequencies, each of the keys may be provided with means for depressing two of the code bars 102. Each pair of code bars when depressed causes the plucking of the corresponding pair of vibrating reeds 100. A common bar 104 operates to shift the contact spring 105 from out of engagement with contact 106 and into engagement with contact 107, whenever any one of the code bars 102 is depressed. Contacts 105, 106 and 107 serve to disconnect the subscriber's telephone transmitter 108 from the line and to substitute the generating coil 101 for the transmission of the code signals.

There may be as many keys in the set 103 as are needed for transmitting the various numeral and letter characters used for telephone designations. Also the number of frequencies comprising the code for each character may be varied if desired. Also it is obvious that the physical structure of the transmitter may assume many different forms. For example, the reed plucking transmitter disclosed in the patent to Mallina, No. 2,147,710 of February 21, 1939, would in general be suitable for use in the present system.

Since the central office battery is disconnected

from the line during designation transmission, it is necessary, as hereinbefore explained, to provide some means whereby the premature replacement of the telephone by the subscriber transmits a signal over the line which will effect the immediate release of the sender. This means comprises a lever 109, which is depressed by the cradle plunger 110 when the subscriber replaces his telephone handset in the cradle of the supporting stand. The lever 109 depresses a single one of the code bars to pluck the corresponding single reed, thereby transmitting a special code of one frequency to the central office. At the same time the downward movement of the lever 109 tensions the spring 111, which is strong enough to rotate the toothed lever 112 about its pivot 113 and to shift the contact spring 116 to its alternate position against the tension of the weaker spring 152. The toothed sector of the lever 112, however, meshes with the pinion attached to the balance wheel 114, which in turn meshes with the fan governor 115. The resistance thus offered by the fan to the tension of the spring 111 introduces an interval of delay between the downward movement of the plunger 110 and the rotation of the lever 112 sufficiently to move the contact spring 116 out of engagement with spring 117. The opening of contact springs 116 and 117 disconnects the generator coil 101 from the line, thus terminating the timed transmission of the special signal current. The contact springs 150 and 151, which are also shifted under control of spring 116, are in the receiver circuit and may be adjusted to open slightly before contacts 116 and 117 open. This avoids acoustic disturbances in the receiver when the direct current circuit is opened.

Central office equipment

At the central office the subscriber's line 120 terminates in a line finder switch F, which is permanently associated through a link circuit with a first or district selector switch S. Selector S has access through succeeding switches, such as an office selector S-1, an incoming selector S-2, and a final selector S-3, to called subscribers' lines. The line finder-district link circuit is automatically associated with an idle register sender by means of a link circuit 121 comprising switches S-4 and S-5.

Although the invention is not limited to a system using any particular type of selector switch, it may be assumed that the switches disclosed in Fig. 1 are of the well-known panel type, such as those disclosed in numerous prior art patents including the patent to Stearn et al. 1,395,977 of November 1, 1921.

The register sender shown in Figs. 2 to 5 includes, in addition to controlling sequence switches 229 and 234 and numerous circuit controlling relays, a receiving circuit for receiving the alternating current signals and for translating them into registrations on the relay registers, which in turn serve to control the selective operation of the switches S, S-1, S-2 and S-3 to establish the desired conversational connections. This alternating current receiving circuit includes a hybrid coil 300, which is coupled through a low-pass filter 301 and an amplifier 302 to a common input circuit 308 for a series of five band-pass filters 303, 304, 305, 306 and 307. These filters correspond respectively to the five reeds 100 of the subscriber's transmitter, each filter serving to pass the frequency produced by the corresponding reed and to exclude all other

signaling frequencies. The output circuits of the filters 303 to 307 are connected respectively to detectors 309, 310, 311, 312 and 313, and the output circuits of these detectors are connected respectively to the operating windings of transfer relays 400, 401, 402, 403 and 404. The transfer relays 400 to 404 serve to operate the register relays shown in Fig. 5. The first three registers 500, 501 and 502 serve to register the three code letters of the office designation; and the next four registers, of which only one is illustrated, namely the units register 503, serve to register the numerical portion of the telephone designation. The transfer relays during the course of the designation transmission are associated successively with these registers and serve to operate the relays of each register in accordance with the corresponding character received over the subscriber's line. After the designation has been registered on the relay registers shown in Fig. 5, the sender proceeds to control the selective operation of the switches in accordance with these registrations.

For the sake of simplicity much of the controlling equipment of the sender has been omitted. For a better understanding of the manner in which senders of this general type operate in the performance of their switch controlling functions reference is made to the prior art patents disclosing these senders in detail, and in particular reference is made to the above-noted patent to Stearn et al., No. 1,395,977; to the Raymond et al. Patent No. 1,862,549 of June 14, 1932; and to the Stearn Patent No. 1,505,171 of August 19, 1924.

Detailed description of operation

The operation of the system will now be described in detail. For this purpose it will be assumed that the subscriber of line 120 wishes to converse with the subscriber of line 122 and that the designation of the called line is CHE-3567.

Initiation of call

To initiate the call the subscriber removes his telephone, which may comprise a handset including the transmitter 108 and receiver 123 in a single structure, from the cradle in the supporting stand. The removal of the weight of the telephone from the button 124 permits the plunger 110 and the lever 109 to move upwardly. The upward movement of the lever 109 releases the depressed code bar 125 and off-normal bar 104. The bar 104 opens contacts 105 and 107 and closes contacts 105 and 106. The bar 109 also releases the tension on spring 111, permitting the lever 112 and contact springs 116 and 150 to be returned by the spring 152 to the position shown in the drawings, thereby closing first contacts 116 and 117 and then contacts 150 and 151. Contacts 105 and 106 and contacts 116 and 117 close the line loop, and contacts 150 and 151 close the receiver circuit. The closed line loop may be traced from conductor 127, through coil 128, transmitter 108, conductor 129, closed contacts 106 and 105, closed contacts 117 and 116 to the other line conductor 130. The closure of this loop circuit initiates the operation of the line finder switch F in the usual manner, the subscriber's line is seized by said finder, the link circuit 121 seizes the line finder-district circuit and also an idle register sender, and the calling line is extended through to the seized sender.

During the extension of the calling line through 75

to the sender the sequence switch 133 of the district selector moves into position 3, and the controlling sequence switch of the link 121 advances to a position for closing the sleeve or control conductor from the district selector through the link to the sender. The path over this control conductor may be traced from battery through the winding of relay 134, contacts of spring 137 and in parallel from battery through the winding of relay 138 through contacts of spring 137, conductor 139, brush of switch S-4, winding of relay 140 in the link circuit, contacts of spring 141 controlled by the link-circuit sequence switch, brush of switch S-5, conductor 210, back contacts of relay 211, back contacts of relay 212 through the middle and right windings of relay 213 to ground. Relays 134 and 140, being marginal, do not operate in this circuit. Relay 213, however, operates and closes an obvious circuit for operating relay 214. Relay 214 operates relay 215, and the latter locks in a circuit through its own front contacts. Relay 215 applies ground to the off-normal or holding conductor 216 for the purpose of holding the various relays that are to be operated in the sender during the course of its progress in controlling the establishment of the desired connection.

A circuit is now closed including a source of direct current, the line relay 200 of the register sender and the extended subscriber's line. This circuit may be traced from battery through resistance 201, normal contacts of relay 202, right winding of line relay 200, normal contacts of relay 203, conductor 204 through the brushes of link switches S-5 and S-4, conductor 131, contacts of spring 132 of the sequence switch 133 associated with the district selector S, normal contacts of relay 134, brush of finder switch F, conductor 127, thence through the closed loop as above traced to conductor 130 through the finder switch F, contacts of relay 134, contacts of sequence switch spring 135, conductor 136 through the brushes of link switches S-4 and S-5, conductor 205, contacts of relay 203, left winding of relay 200, normal contacts of relay 202, resistance 206, normal contacts of relay 201 to ground. Relay 200 operates and closes a circuit from battery through the winding of relay 202, front contact of relay 200 to ground through the back contacts of relay 201. Relay 202 operates and locks in a circuit from battery through its winding and front contact through the back contact of relay 208 to the grounded holding conductor 216. Relay 202 in operating disconnects battery and ground from the windings of relay 200 and from the calling subscriber's line. Relay 200 thereupon releases and closes an operating circuit for slow-release relays 217 and 218. The circuit for these relays may be traced from battery through their windings in parallel thence through the front contact of relay 202, back contact of relay 200 to ground through the back contact of relay 201. Relay 217 disconnects the grounded bridge and extends the transmission circuit from the calling subscriber's line through to the input circuit 219 of the hybrid coil 300.

During the interval that direct current is flowing over the subscriber's line following the seizure of the sender a test of the line is made to determine its relative resistance for the purpose of adjusting the intensity of the key tone current which is transmitted from the sender to the subscriber's station as a signal to him that he may proceed to send the desired designation. The purpose for making this adjustment is to ob-

tain a uniformity in the key tone for subscribers' lines of varying lengths and resistances. The mechanism for making the adjustment includes vacuum tube 314, a plurality of gas-filled tubes 315, 316, 317 and 318, and associated relays for connecting a variable number of shunt resistances across the secondary winding of the dial tone transformer 319. Normally the grid electrode of the vacuum tube 314 is free from bias, and maximum current flows from battery 320 through resistance 321 and the anode circuit of the tube to ground. The flow of current through the resistance 321 lowers to a minimum value the voltage applied across the control gaps of the discharge tubes 315 to 318, and none of these tubes operates. When, however, the calling line 120 is extended to the sender and battery is applied thereto through the windings of relay 200, as above described, a negative potential is applied to the grid of tube 314, the value of which is somewhat proportional to the resistance of the subscriber's line. This bias reduces the flow of current through resistance 321 and increases the voltage applied across the control gaps of tubes 315 to 318 by a corresponding amount. These latter tubes are arranged to ionize at voltages of different values, and these voltages are obtained by connecting the control gaps of the tubes to different tap points on the secondary winding of transformer 324. That is to say, tube 315 will ionize at a minimum voltage, tube 316 at a larger voltage, tube 317 at a still larger voltage, and so forth. Assume, therefore, that the resistance of the calling line 120 is such that the first two tubes 315 and 316 ionize. The circuit for the control gap of tube 315 may be traced from battery 320, resistance 321, resistance 322, the control gap of tube 315, right winding of relay 323 through a portion of the secondary winding of transformer 324 to ground. The tube ionizes, and current now flows in the anode circuit which may be traced from battery 336, contact of relay 337, which operated when ground was applied to conductor 216, anode gap of the tube 315, right winding of relay 323 to ground through the secondary winding of the transformer 324. Relay 323 operates in this circuit and locks in a circuit from battery through its left winding and front contact, conductor 326, front contact of relay 200 to ground at the back contact of relay 207. As soon as relay 202 operates following the operation of relay 200, the locking circuit of relay 323 is closed over conductor 326 through the front contact of relay 202 and the back contact of relay 208 to the grounded conductor 216. In a similar manner the tube 316 is ionized and relay 327 is operated and locked to the grounded conductor 326. When the central office battery is disconnected from the subscriber's line, the bias on tube 314 is removed, and full current flows again through the resistance 321. The control gaps of the operated tubes 315 and 316 are now ineffective, but the tubes and relays are held until the control ground is later removed from conductor 216. Relay 323 traces a shunt across the transformer 319 traceable from one terminal of the transformer winding over conductor 328, contacts of relay 323, conductor 329, resistance 330 to the other terminal of the transformer winding. Relay 327 closes a similar shunt circuit including resistance 331. The relay 332 having operated to connect the key tone source to the primary winding of transformer 329, tone current, controlled in intensity by the shunt resistances 330 and 331, is trans-

mitted through a suitable filter 333 over the transmission circuit to the subscriber's station.

Subscriber sends called designation

5 The calling subscriber hears the dial tone and proceeds to transmit the desired telephone designation CHE-3567 by depressing, one after the other, seven of the keys 103. The first three of these keys bear the letters C, H and E, respectively, the numerical equivalents of which are 2, 4 and 3, respectively. The last four keys depressed bear the numerals 3, 5, 6 and 7, respectively. Each key depressed causes the simultaneous plucking of two reeds 100. These reeds 100 vibrate in the magnetic field and generate currents of corresponding frequencies in the coil 101. These alternating currents are transmitted over the circuit to the hybrid coil 300 from whence they pass through a selecting filter 301 to amplifier 302. Here the alternating currents are amplified and applied to the common input circuit 308 of the band-pass filters 303 to 307, inclusive. The common input circuit 308 is also connected to an enabler 334 which controls the operation of the detectors 309 to 313, inclusive. These alternating current receiving circuits, which receive the signal currents and utilize them for registering the telephone designation, are illustrated diagrammatically herein since they are not particularly concerned with the features of the present invention. These circuits may, however, be of any suitable type and in general may be the same as those disclosed in the patent of A. A. Lundstrom, No. 2,237,742 of April 8, 1941.

When, therefore, the calling subscriber depresses the key, such as key 142, corresponding to the letter C, two of the code bars 125 and 143 are actuated to pluck the corresponding reeds 144 and 145. The common bar 104 is depressed by the actuated code bars and remains depressed until the subscriber releases the actuated key 142. The bar 104 in its depressed position shifts the contact spring 105 to complete the transmission circuit for transmitting currents of frequencies corresponding to reeds 144 and 145 over the line 120 to the receiving mechanism in the central office sender. This transmission circuit may be traced from the input circuit of the hybrid coil 300 over conductor 200, left front contacts of relay 217, condenser 221, contacts of relay 203, conductor 205 through the link 121, conductor 136, contacts of spring 135, normal contacts of relay 134, brush of finder F, conductor 130, contacts 116 and 117, contacts 105 and 107, through the generating coil 101, conductor 127, brush of finder F, contacts of relay 134, contacts of spring 132, conductor 131, through the link 121, conductor 204, contacts of relay 203, condenser 222, right front contacts of relay 217 and conductor 223 to the input circuit of the hybrid coil 300. If it is assumed that the frequencies of the five reeds 100 are, beginning with reed 144, f_a , f_b , f_c , f_d and f_e , the actuation of key 142 causes currents of frequencies f_a and f_e to be transmitted simultaneously over the circuit above traced to the hybrid coil 300. Coil 300 passes these currents to the conjugate branch including the filter 301, and they are amplified by the device 302 from whence they are applied to the common input circuit 308. These currents are then selected by the filters 303 and 307, respectively, and applied to the detectors 309 and 313. Detector 309 responds to current of frequency f_a , and operating current flows through

the winding of translator relay 400. Similarly the detector 313 responds to current of frequency f_a , and operating current flows through the winding of relay 404. Relays 400 and 404 lock through their windings and contacts, conductor 405, closed contacts of relay 406 to the grounded off-normal conductor 216. Relay 406, it will be noted, operates as soon as ground potential is applied to conductor 216, the operating circuit of relay 406 extending through the normal contact of relay 407. As long as the transfer relays 400 to 404 are all in their normal positions, the grounded conductor 216 is extended through normal contacts of these relays to conductor 408. With ground connected to conductor 216, condenser 411 is charged, and the armature of relay 407 is held against the left-hand contact by the current that flows through the lower winding. When one of the relays, 400 to 404, operates, the ground through resistance 410 is removed. The current through the lower winding of relay 407 reverses and tends to move the armature to the right-hand contact. However, the discharging current of condenser 411 flowing through the upper winding tends to hold the armature on the left-hand contact, and thus the movement of the relay armature from left to right is delayed until the discharge current of the condenser becomes small. After an interval measured by this discharging time of condenser 411 the relay 407 operates and releases relay 406.

While the relay 407 is measuring the time interval above mentioned, transfer relays 400 and 404 are operated and locked in the circuits traced. Relays 400 and 404 close a circuit traceable from the grounded conductor 216, through the operated contacts of relay 400, conductor 412, closed contacts of relay 404, conductor 413 through the closed contacts of switching relay 504, winding of register relay 505 to battery. It should be explained that relay 504 is in an operated condition at this time over a circuit traceable from battery through its winding, normal contacts of relay 506 thence over conductor 507 which was grounded following the seizure of the sender. Register relay 505 operates and prepares a locking circuit traceable from battery through its right winding and contact, winding of relay 506 thence through the back contacts of relays 508, 509, 510 in series to conductor 511. As soon as relay 407 completes the measurement of the time interval it releases relay 406, which extends the register locking circuit through its make contact to grounded conductor 216 before ground is removed from conductor 405. Hence the register relay 505 locks over the circuit above traced through conductor 511 and the back contact of relay 406 to conductor 216 before ground is removed from conductor 405 to cause the release of transfer relays 400 and 404. The operated register 505 and relay 506, which operates in series therewith, remain energized in a permanent locking circuit which may be traced from battery through the right winding and contact of register relay 505, winding and front contact of relay 506 to the grounded control conductor 507. Relay 506 releases the switching relay 504 and closes an obvious operating circuit for the switching relay 508 corresponding to the next office register 501. Thus the transfer relays are disconnected from the register 500 and associated with the register 501 ready for the registration of the next designation character. When the armature of relay 407 moves to the right-hand contact, it connects ground to lead 425. This reverses the

current through the lower winding which then tends to move the armature to the left-hand contact. The charging current of the condenser, however, delays this action for a period sufficient to insure the release of relay 406, the operation of relays 506 and 508 and the release of relay 504. The release of relays 400 and 404 restores the ground to conductor 408 which holds the armature of relay 407 on the left hand contact until the next digit signal is received.

When the calling subscriber depresses the second key for the letter H, two reeds are plucked for generating and transmitting currents having frequencies f_a and f_c . These currents are selected by filters 303 and 305 resulting in the operation of transfer relays 400 and 402. During the timed operation of relay 407 these operated transfer relays close a register operating circuit from the grounded conductor 216, contacts of relay 400, conductor 414, contacts of relay 402, conductor 415, contacts of relay 503, left winding of relay 512 to battery. Register relay 512 closes a circuit through its right winding and contact, winding of relay 513 thence through series contacts of relays 509 and 510 to ground over conductor 511 as soon as relay 406 releases. Relay 513 also operates in this circuit and closes a locking circuit for register relay 512 and for itself to the grounded control conductor 514. When relay 406 releases, transfer relays 400 and 402 release since, in the meantime, the enabler 334 has desensitized the vacuum tube detectors. Relay 407 now times an interval and releases to reoperate relay 406.

In the manner above described the calling subscriber manipulates the keyboard to transmit the remaining letter E of the office designation and the numerical digits 3, 5, 6 and 7. The transmission of the letter E results in the operation of transfer relays 400 and 403, whereupon the register relays 515 and 516 are operated and locked. The transmission of the thousands, hundreds and tens digits, 3, 5 and 6, causes the operation of the proper register relays of the thousands, hundreds and tens registers, which have been omitted from the disclosure for the sake of simplicity. Finally the transmission of the units digit 7 causes the operation of transfer relays 402 and 403, and relays 517 and 518 of the units register 503 are energized and locked.

During the time the transmission circuit is closed between the substation of the calling line 120 and the hybrid coil 300, the central office battery is disconnected from the subscriber's line. As soon as relay 202 operates following the seizure of the sender the central office battery is disconnected from the line and remains disconnected therefrom throughout the interval that the subscriber is transmitting the designation. Since the transmission circuit between the substation and the central office sender involves numerous relay and switch contacts, it is found that the resistance of the transmission circuit to the flow of the alternating current signals is considerably greater and is subject to wider variations than would be the case if direct current were flowing in the circuit during the signaling period. This disadvantage, however, is obviated by connecting a source of current 224 of relatively high frequency to the transmission circuit. The current from source 224, which may have a frequency of 30 kilocycles, flows over the transmission circuit and has the effect of holding the resistance of the circuit to values comparable with those existing when direct current is flowing.

Connection established in central office

Following the registration of the designation on the registers shown in Fig. 5 the sender progresses through its various stages of operation, and the district and office selector switches S and S-1 are selectively positioned in accordance with the office designation, and the incoming and final selectors S-2 and S-3 are positioned under the control of the sender in accordance with the registered numerical designations. After 10 selections have been completed the relay 212 is operated in the sender to remove the short circuit from the high resistance left winding of relay 213. The inclusion of this resistance in the control circuit causes the release of marginal relay 138, which at this time is operated in series with relay 213. Relay 138 releases and advances the district selector sequence switch 133 to some position, such as position 12. In position 12 of the district selector, ground potential is connected through sequence switch spring 146 to the control conductor 210 thus causing the release of relay 213 in the sender. Relay 213 releases 15 relay 214, and a circuit is closed from battery through the winding of relay 211, front contact of relay 215 to ground at the back contact of relay 214. Relay 211 operates and locks over conductor 210 to ground in the district selector. Relay 225 now operates in a circuit from battery through its winding to ground at the contact of relay 211. Relay 225 closes a circuit through resistance 226 in shunt of the relay 215 and relay 215 releases. Ground is now maintained on the holding conductor 216 at the front contact of relay 211.

Following the advance of the district selector sequence switch to the proper talking position, relay 207 is operated in the sender. Relay 207 closes a circuit from battery through resistance 227, contact of relay 207, front contact of relay 211, thence to control conductor 210 in parallel with the winding of relay 211. These parallel circuits increase the current flowing in conductor 210 sufficiently to cause the operation of the marginal relay 140 in the link circuit 121. Relay 140 causes the release of the link circuit 121 and the opening of the circuits extending to the sender. Thereupon relay 211 releases and removes holding ground from the conductor 216, resulting in the release of all operated relays in the sender. Thus the register sender is restored to its normal position following the completion of its functions in the establishment of the desired connection.

Abandonment of call

It will be assumed next that the calling subscriber abandons the call at some time prior to the completion of the operation of the selective switches. In such a case it is, of course, desirable to effect the immediate release of the register sender in order that it may be available for other calls. When the calling subscriber replaces his telephone to abandon the call before the connection is completed, a special signal is transmitted to the register sender to notify it to release at once. If the abandonment occurs while the designation is being sent, relays 213, 214, 215, 202, 217 and 218 are in an operated condition.

The transmission to the sender of the special signal at this time is caused by the depression of plunger 110 when the telephone engages the button 124 as it is replaced in the cradle of the supporting stand. The depression of the plunger

110 rotates the lever 109 to operate the single code bar 125 which plucks the reed 144 corresponding to frequency f_a . Lever 109 also tensions the spring 111 for causing the rotation of lever 112 to shift the spring 116 after a delay interval caused by the resistance the fan 115 offers to the gear wheel 114. The single frequency signal transmitted over the line is received by the sender to cause the operation of transfer relay 400 in the manner above described. Relay 400 closes a circuit from the grounded conductor 216 through its front contact, conductor 416, back contacts of relays 417 and 418, switch 419, back contact of relay 420, back contact of relay 404, conductor 421 through the winding of relay 208 to battery. Relay 208 operates and locks through its own front contact to the grounded holding conductor 216. Relay 208 opens the circuit of relay 202 and connects battery and ground through resistances 201 and 206 through the windings of relay 200 to the subscriber's line circuit. The purpose of connecting relay 200 to the line circuit at this time is to make a test to determine whether the subscriber has replaced his telephone permanently or momentarily. Since it was assumed he abandoned the call, the loop is open, and relay 200 fails to operate. Therefore, relay 202 releases and opens the circuit of slow-release relays 217 and 218. When relay 218 releases, time measuring sequence switch 229 having advanced to the proper position, a circuit is closed for operating relay 230. This circuit may be traced from battery through the winding of relay 230, contacts of spring 231 on the switch 229, conductor 232, back contacts of relay 218, back contacts of relay 207, back contacts of relay 212 to the grounded conductor 216. Relay 230 locks through its own contact directly to the grounded conductor 209. Relay 230, when operated, closes an obvious operating circuit for relay 207. Relay 230 also closes a short circuit around the right winding of relay 213. This short circuit reduces the resistance in series with relay 134 in the district selector sufficiently to permit this relay to operate. Relay 134 opens the talking conductors and in the well-known manner causes the district sequence switch 133 to advance, bringing about a restoration of the district selector, if the same has been operated, and the release of the circuits to their normal condition. When the district selector sequence switch reaches position 11, ground potential is connected to the control conductor 210 through the contacts of spring 146. Relays 213 and 214 in the sender release. Relay 211 operates as above described and connects battery through the resistance 227 and the front contact of relay 207 to the control conductor 210. The link circuit 121 also releases at this time, and the sender is disconnected from the line finder-district link. The sender now fully restores to its normal condition ready for the next use.

Accidental manipulation of substation equipment

If the calling subscriber, instead of abandoning the call, merely depresses the button 124 momentarily either accidentally or otherwise, the sender will receive the disconnect signal the same as before, but in this instance it will determine by test that the subscriber does not intend to abandon the call. Since the line loop recloses following the transmission of the release signal, relay 200 reoperates when reconnected to the line loop following the operation of relay 208 and the release of relay 202 and before relays 217 and 218

have time to release. The operating circuit for relay 200 may now be traced through the front contacts of relay 208 and thence to battery and ground through resistances 201 and 206. Relay 200 holds in this circuit following the reoperation of relay 202. Relay 200 in operating recloses the operating circuit of relay 202, and the latter relay closes a new holding circuit for relays 217 and 218. This holding circuit may be traced from battery through the windings of relays 217 and 218 in parallel, front contact of relay 202, front contact of relay 208 to ground through the back contact of relay 207. Thus relay 218 is prevented from releasing, and relays 230 and 207 do not operate under these conditions. Relay 208 closes a circuit for sending the subscriber a special tone signal which he will recognize as an instruction that he should replace his telephone and initiate the call again. Current for the reorder tone flows from the source 228 through the front contacts of relay 208 thence through condensers 221 and 222 over conductors 204 and 205 and over the loop of the calling line to the subscriber's receiver 123. When the calling subscriber replaces his telephone in response to the reorder tone, relay 200 releases and opens the holding circuit of relay 202. Relay 202 releases and causes the release of slow relays 217 and 218. Thereupon the sender proceeds as above described to restore to its normal condition.

It was assumed herein that the special release signal consisted of an alternating current of a single frequency. Either of the frequencies f_a , f_b or f_c may be used singly, in which case the switch 419 in Fig. 4 is closed as illustrated, and switches 422 and 423 are open. If it is desired to use frequencies f_d or f_e alone, switch 423 should be closed and switches 419 and 422 opened. Also frequency f_a may be used by closing the switch 422 and opening switches 419 and 423. Also other combinations may obviously be employed.

What is claimed is:

1. In a telephone system, a subscriber's line having a substation, automatic switches, a sender common to said switches, means responsive to the closure of said line at the substation for seizing said sender and for establishing a connection between said line and said sender, a source of current included in the established connection for supplying current thereto, means for disconnecting said source from said established connection between the line and sender without releasing said sender, means for transmitting designations over said line to said sender, means in said sender for controlling said switches in accordance with the designations received, means responsive to the replacement of the subscriber's telephone at said substation for transmitting a signal over said line, and means in the sender responsive to said signal for effecting the release of said sender.

2. In a telephone system, a subscriber's line having a substation, automatic switches, a sender common to said switches, means responsive to the closure of said line at the substation for seizing said sender and for extending said line to said sender, a source for supplying current to said line, means for including said source in circuit with said line and for disconnecting it from said line, means independent of said source for holding said sender, means for transmitting designations over said line to said sender, means in said sender for controlling said switches in accordance with the designations received, means for releasing said sender following the comple-

tion of its switch-controlling functions, means at said substation for transmitting a release signal over said line, and means effective if said signal is received before the sender has completed its functions for causing the immediate release of said sender.

3. In a telephone system, a telephone line, automatic switches, a controlling mechanism for said switches, means responsive to the closure of said line for seizing said mechanism and for connecting said line thereto, a source of current in circuit with said line for energizing the same, means for disconnecting said source from the line, means for holding said mechanism after the disconnection of said source, means for sending telephone designations over said line, means in said mechanism for receiving and utilizing said designations to control said switches, means for sending a release signal over said line, and means responsive to said signal for effecting the release of said mechanism.

4. In a telephone system, a subscriber's line, automatic switches, a transmitter at the substation of said line for transmitting telephone designations over said line, a sender, means controlled over said line for connecting it to said sender and for holding the sender in a seized condition unaffected by the flow of current in said line during the transmission of designations, means in the sender for receiving and utilizing the transmitted designations to control said switches, and means controlled over said line for releasing the seized sender.

5. In a telephone system, a telephone line, automatic switches, a sender for controlling said switches, means responsive to the initiation of a call on said line for extending the line to said sender, a source for supplying current from said sender to said line when the latter is connected to the sender, means responsive to the current flowing from said source over said line for disconnecting said source from said line, means for sending telephone designations over said line to the sender after said source of current has been disconnected, means in said sender for receiving said designations and for utilizing them to control the selective operation of said switches, and means for transmitting a signal over said line to the sender to cause the release of said sender.

6. In a telephone system, a subscriber's line, automatic switches, a transmitter at the substation of said line for transmitting over said line alternating currents of different frequencies representing a telephone designation, a sender, means responsive to the initiation of a call on said line for connecting it to said sender and for maintaining the sender in a seized condition unaffected by the flow of current in said line during the transmission of the telephone designation, means in the sender for receiving and utilizing the designation currents to control said automatic switches, and means controlled over said line in response to the replacement of the subscriber's telephone for releasing the sender.

7. In a telephone system, a subscriber's line, automatic switches, a transmitter at the substation of said line for transmitting telephone designations over said line, a sender, means responsive to the closure of said line for seizing said sender, a control circuit including said line established between the sender and said substation following the seizure of the sender, a source for causing direct current to flow over said control circuit, means controlled by the flow of direct current in said control circuit for pre-

paring the sender to receive said telephone designations, means for holding said sender independently of the flow of direct current in said line, means in the sender for receiving and utilizing the transmitted designations to control said switches, and means controlled over said line for releasing said sender.

8. In combination, a telephone line, automatic switches, a register sender, means for connecting said line to said register sender, a source of current included in the connection established between said line and sender for supplying current to said line, a transmitter for transmitting telephone designations over said line, means for disconnecting said source to prevent the flow of current therefrom over said line while said designations are being transmitted, means for holding said register sender while said source is disconnected, means in the register sender for receiving and utilizing the transmitted designations to control said switches, and means for releasing said register sender.

9. In a telephone system, a telephone line, automatic switches, a transmitter at the substation of said line for transmitting telephone designations over said line, a sender, means controlled over said line for connecting it to said sender, releasing means for said sender unaffected by the condition of said line during the transmission of said telephone designations thereover, means in the sender for receiving and utilizing transmitted designations to control said switches, means responsive to the replacement of the subscriber's telephone for sending a release signal over said line, means for discontinuing the transmission of said release signal at the end of a predetermined interval following the replacement of said telephone, and means responsive to said signal for effecting the release of said sender.

10. In a telephone system, a telephone line, automatic switches, a transmitter at the substation of said line for transmitting telephone designations over said line, a sender, means controlled over said line for connecting it to said sender, releasing means for said sender unaffected by the condition of said line during the transmission of said telephone designations thereover, means in the sender for receiving and utilizing transmitted designations to control said switches, means responsive to the replacement of the subscriber's telephone for opening said line to discontinue the calling condition thereof and for generating and transmitting a release signal over said line to said sender, a delay mechanism responsive to the replacement of said telephone for terminating after an interval the transmission of said release signal, and means responsive to said release signal for causing the release of said sender.

11. In a telephone system, a subscriber's line, automatic switches, a transmitter at the substation of said line comprising a plurality of vibratory reeds having different frequencies, means controlled by the subscriber for plucking said reeds in different combinations to transmit currents over said line representing a telephone designation, a sender, means responsive to the closure of said line for connecting it to said sender, means in the sender responsive to the

designation currents transmitted over said line by said transmitter for controlling the selective operation of said switches, means responsive to the replacement of the subscriber's telephone for plucking one of said reeds to transmit a release signal over said line, and means responsive to said signal for effecting the release of said sender.

12. In a telephone system, a subscriber's line, automatic switches, a transmitter at the substation of said line comprising a plurality of vibratory reeds having different frequencies, means controlled by the subscriber for plucking said reeds in different combinations to transmit currents over said line representing a telephone designation, a sender, means responsive to the closure of said line for connecting it to said sender, means in the sender responsive to the designation currents transmitted over said line by said transmitter for controlling the selective operation of said switches, a time delay mechanism associated with said transmitter, means responsive to the replacement of the subscriber's telephone for initiating the operation of said delay mechanism and for plucking one of said reeds to transmit over the line a signal current of corresponding frequency, means in said sender responsive to said signal current for effecting the release of said sender, and means operated by said delay mechanism at the end of a predetermined interval for disconnecting said transmitter to terminate the sending of said signal.

13. In a telephone system, a telephone line, automatic switches, a sender for controlling said switches, means responsive to the closure of said line for connecting the same to said sender, a control relay in said sender, a source of current connected to said telephone line through the winding of said relay, means responsive to the operation of said relay in a circuit including said telephone line for disconnecting said source of current from said line, means for transmitting telephone designations over said line to said sender after said source of current has been disconnected therefrom, and a source for supplying alternating current to said line to control the impedance thereof during the transmission of said telephone designations.

14. In a telephone system, a telephone line, automatic switches, a sender for controlling said switches, means responsive to the closure of said line for connecting the same to said sender, a control relay in said sender, a source of current connected to said telephone line through the winding of said relay, means responsive to the operation of said relay in a circuit including said telephone line for disconnecting said source of current from said line, transmitting means for sending over said line alternating currents of different frequencies representing telephone designations, and means for controlling the resistance of said line during the transmission of said alternating currents, said means comprising a source for supplying alternating current to said line of a frequency beyond the range of frequencies employed for representing said telephone designations.
